UNITED STATES PATENT OFFICE.

HANS GRAF HOYOS, OF HANOVER, GERMANY.

INFLATABLE BOOT-TREE.

SPECIFICATION forming part of Letters Patent No. 763,489, dated June 28, 1904.

Application filed February 24, 1903. Serial No. 144,842. (No model.)

To all whom it may concern:

Be it known that I, HANS GRAF Hoyos, lieutenant, a subject of the German Emperor, and a resident of Hanover, Germany, have 5 invented new and useful Improvements in Inflatable Boot-Trees, of which the following is a specification.

This invention relates to inflatable boot-trees, the construction of which is improved 10 in such a manner that a uniform pressure can be exerted by the tree on all parts of the boot, so that—for example, in top-boots—the folds in the boot are well smoothened.

In the accompanying drawings the device 15 is shown in Figure 1, in a side view, adapted to be used with top-boots. Fig. 2 represents the apparatus, in a side view, in the construction to be used for ordinary boots or shoes. Fig. 3 shows the valve on a larger scale.

20 The device consists of the inflatable body *a*, which is made from air-tight material and in the shape of a stocking of proper size and form. The inflatable body *a* is closed at the top by a cap *b*, which is made from hard material, such as thick leather or the like, which does not collapse if the air is let out of the main body *a*. On the top of said cap *b* a return-valve *c* is provided, through which the inflatable main body *a* can be inflated by 25 means of an air-pump in the well-known manner.

To the bottom of the inflatable part *a* a sole *h*, of solid material, is fixed in any suitable manner, which is connected with the solid head 35 *b* by means of a strip *e* of non-stretchable material which is as long as the boot is high. A metal shield *d*, which corresponds in shape to the upper of the boot, is fixed at its upper end to the lower end of the cap *b*. If the 40 inflatable boot-tree is to be used with top-boots, the shield *d* is made of two parts, as shown in Fig. 1, hinged together at one point *g*, and ribbons *f* are fixed to the upper end of the shield *d* for the purpose of keeping the shield 45 in proper position on the inflatable body *a*. The inflatable boot-tree for top-boots further has a handle *k* fixed to the upper edges of the shield *d*, so as to facilitate the removal of the boot-tree.

50 This inflatable boot-tree is used in the following manner: The inflatable body *a*, with sole *h* and shield *d*, is inserted into the boot.

The cap *b* rests on the upper edge of the boot. If now the inflatable body *a* is inflated in the well-known manner, a uniform pressure is exerted by means of the shield *d* on the front and upper part of the boot. All deformities in the boot formed, for example, by bunions, corns, and the like are preserved, as the soft wall of the inflatable boot *a* fills them out. The 55 connection of the solid top part and the solid sole prevents any excessive lateral inflation of the inflatable boot at the upper edge.

Having fully described my invention, what I claim, and desire to secure by Letters Patent, is—

1. Improved inflatable boot-tree comprising in combination an inflatable body of flexible material in the shape of a stocking of a size corresponding to the boot, a cap of rigid 70 material closing the inflatable body at the upper end, a return-valve in said cap, a sole of stiff material at the bottom of the inflatable body, a strip of non-stretching material connecting the stiff cap and sole, a shield of sheet 75 metal corresponding in shape to the upper of the boot fixed at the upper end to the front of the cap, substantially as described and shown and for the purpose set forth.

2. Improved inflatable boot-tree comprising in combination an inflatable body of flexible material in the shape of a stocking of a size corresponding to the boot, a cap of rigid 80 material closing the inflatable body at the upper end, a return-valve in said cap, a sole of stiff material at the bottom of the inflatable body, a strip of non-stretching material connecting the cap and sole, a shield of sheet metal corresponding in shape to the upper of the boot fixed at the upper end to the front of 85 the cap, consisting of two hinged parts, the upper one corresponding in shape to the leg of a top-boot and the lower one corresponding in shape to the upper of the boot, substantially as described and shown and for the 90 purpose set forth.

In testimony whereof I have hereunto set my hand in presence of two subscribing witnesses.

HANS GRAF HOYOS.
